US00D831724S

(12) **United States Design Patent** (10) Patent No.: **US D831,724 S**
Bergstrom et al. (45) Date of Patent: **** Oct. 23, 2018**

(54) **MONITORING CAMERA**

(71) Applicant: **AXIS AB**, Lund (SE)

(72) Inventors: **Morten Bergstrom**, Bjarred (SE); **Jens Pahlitzsch**, Lund (SE); **Mathias Walter**, Arlov (SE); **Niclas Moller Lewin**, Malmo (SE); **Johan Bergsten**, Landskrona (SE)

(73) Assignee: **AXIS AB**, Lund (SE)

(**) Term: **15 Years**

(21) Appl. No.: **29/634,118**

(22) Filed: **Jan. 18, 2018**

Related U.S. Application Data

(60) Continuation of application No. 29/551,566, filed on Jan. 14, 2016, which is a division of application No. (Continued)

(57) **CLAIM**

The ornamental design for a monitoring camera, as shown and described.

DESCRIPTION

FIG. 1 is a bottom, left, rear perspective view of a monitoring camera in accordance with our design;

FIG. 2 is a rear elevational view thereof;

FIG. 3 is a bottom view thereof;

FIG. 4 is a right side elevational view thereof;

FIG. 5 is a left side elevational view thereof;

FIG. 6 is a front elevational view thereof; and,

FIG. 7 is a top plan view thereof.

The broken lines depict portions of a monitoring camera in which the design is embodied and form no part of the claimed design.

1 Claim, 4 Drawing Sheets
